(Cl. D64—11)

To all whom it may concern:

Be it known that we, Alvin E. Schubert, Theodore G. Clement, and John F. Egan, citizens of the United States of America, residing in Rochester, county of Monroe, State of New York, have invented a new, original, and ornamental Design for a Document Copying Apparatus, of which the following is a specification, reference being had to the accompanying drawings, forming a part thereof, in which

Fig. 1 is a perspective view taken from the front and side of a document copying apparatus, showing our new design; and

Fig. 2 is a perspective view taken from the back and side of the apparatus shown in Fig. 1.

We claim:

The ornamental design for a document copying apparatus, as shown.

ALVIN E. SCHUBERT.
